ROCK DRILL

Frank E. Sinclair, Claremont, N. H., assignor to
 Sullivan Machinery Company, a corporation of
 Massachusetts

Application December 30, 1937, Serial No. 182,550

12 Claims. (Cl. 121—7)

This invention relates to rock drills, and more particularly to improvements in the rotation mechanism for the drill steel of a hammer rock drill.

- 5. An object of this invention is to provide an improved drill steel rotation mechanism for a rock drill. Another object is to provide an improved drill steel rotation mechanism having improved release means for interrupting drill steel
- 10. rotation at will and embodying improved control means for the rotation release means. A further object is to provide, in a drill steel rotation mechanism of the intermittent ratchet and pawl type operated by the hammer piston
- 15. of the drill motor, improved rotation release means controlled by the throttle valve of the drill, whereby drill steel rotation may be interrupted at will while the hammer motor continues to operate. A still further object is to provide an im- 20 proved fluid actuated plunger device having a conveniently located control valve whereby the rotation release means may be quickly and easily operated. Another object is to provide improved rotation release means for a rock drill of the
- 25. stoper type, whereby rotation of the drill steel may be interrupted during starting or spotting of a drill hole. These and other objects and advantages of the invention will, however, herein- 30 after more fully appear.
- 30. In the accompanying drawings there are shown for purposes of illustration two forms which the invention may assume in practice.

In these drawings:

- Fig. 1 is a view in longitudinal vertical section through a rock drill in which the preferred illustrative embodiment of the invention is incorporated.

- Fig. 2 is a fragmentary view in longitudinal vertical section illustrating a portion of the im- 40 proved rotation release means, the view taken substantially on line 2—2 of Fig. 4.

Fig. 3 is an enlarged cross sectional view taken substantially on line 3—3 of Fig. 1.

- Fig. 4 is an enlarged cross sectional view taken 45 substantially on line 4—4 of Fig. 1.

Fig. 5 is a fragmentary sectional view taken in the plane of Fig. 2, showing the control valve in a different position.

- Fig. 6 is a view in longitudinal vertical section through a rock drill within which a modified form of the invention is embodied.

Fig. 7 is an enlarged rear end elevational view of the rock drill shown in Fig. 6.

- Fig. 8 is a fragmentary sectional view taken 55 substantially on line 8—8 of Fig. 6.

Fig. 9 is a view in longitudinal horizontal section taken substantially on line 9—9 of Fig. 7, showing a portion of the improved rotation release control means.

Fig. 10 is a detail sectional view taken on line 49—49 of Fig. 9.

Fig. 11 is a fragmentary view taken in the plane of Fig. 8, showing the control valve in a different position.

In the illustrative embodiment of the invention shown in Figs. 1 to 5, inclusive, the improved rotation release mechanism, generally designated 1, is shown embodied in a hammer rock drill of the stoper type having a drilling motor generally designated 2 and drill steel rotation mechanism generally designated 3, with which the improved rotation release means is associated. Although the invention is shown embodied in a rock drill of the stoper type, it will be evident, however, that the invention may be embodied in rock drills of various other types. The drilling motor disclosed herein is of the pressure fluid actuated hammer type comprising a cylinder 4 containing in its bore 5 a reciprocatory hammer piston 6. The hammer piston has a forwardly projecting striking bar 7 adapted to strike against a tappet 8 through which the impact blows of the hammer piston are transmitted to the shank of a drill steel 9, in a well known manner. The piston striking bar is guided in a bore in a front cylinder head 10; and arranged in a bore 11 formed in the rearward portion of the cylinder and in axial alignment with the cylinder bore, is a rear cylinder head 12. This rear cylinder head also constitutes a valve box 35 having a rear cover 13, the latter also arranged in the bore 11 and abutting the rear face of the valve box. The valve box cover 13 has a sleeve-like projection 14 extending axially through the valve box and fitted at its forward 40 end within a bore formed in the valve box, and arranged within a valve chamber 15 formed by the cooperating parts 12, 13 and 14 is an automatic fluid actuated fluid distributing valve 16 for controlling the flow of motive fluid to the 45 opposite ends of the cylinder bore to effect reciprocation of the hammer piston. Arranged in a bore 17 formed in a rear head block 18 attached to the rear end of the motor cylinder, is a throttle valve 19 having a control handle, 50 and this throttle valve is formed with an internal chamber 20, to which pressure fluid may be supplied through a supply connection 21 from any suitable source of pressure fluid supply. This throttle valve controls the flow of pressure fluid 55

from the chamber 20 through a port 22 in the valve and a passage 23 in the head block to a pressure chamber 24, the latter connected through longitudinal passages 25 to the fluid 5 supply chamber 26 of the valve box. As the distributing valve 16 and its associated distributing passages do not per se enter into this invention and are of a conventional design, further 10 illustration and description thereof are considered unnecessary.

The means operated by the hammer piston for rotating the drill steel comprises a circular plate member 27 arranged in the bore 11 between the head block 18 and a ratchet ring 28, the 15 forward face of the latter abutting the rear surface of the valve box cover. The parts 12, 13, 27 and 28, arranged in the bore 11, are held in assembled relation by the rear head block 18, and are held against rotation in the bore 11 by a 20 dowel pin 29. Rotatably mounted in aligned bores formed in the parts 13 and 27 is a rifle bar 30 having spiral grooves 31 slidably interlocked with spiral lugs formed on a rifle nut 32 secured within the hammer piston; and formed integral 25 with this rifle bar is a pawl carrier 33 carrying a plurality of spring-pressed pawls 34 engageable with the internal ratchet teeth 35 of the ratchet ring 28. From the foregoing, it will be evident that when the parts are in the position 30 shown in Fig. 1 and the hammer piston is moving forwardly to effect its working stroke, i. e. to deliver a blow through the tappet 8 to the drill steel shank, the rifle bar 30 is rotated by the rifle nut 32 fixed to the piston, and the pawls 35 of the pawl carrier slip over the teeth of the ratchet ring so that the piston strikes an unimpeded blow to the ratchet. Upon reverse movement of the hammer piston, the pawl carrier is held stationary by the pawls engaging the teeth 40 of the ratchet ring, thereby holding the rifle bar 30 against rotation; and as a result, the hammer piston, due to its connection by the rifle nut with the rifle bar, is given a rotary motion. The rotary motion of the piston, as it 45 moves rearwardly, is transmitted through straight grooves 36 on the piston striking bar, slidably interlocked with straight keys on a chuck nut 37 secured within a chuck sleeve 38. The chuck sleeve is rotatably mounted within a 50 front chuck housing 39 secured to the forward end of the motor cylinder and has secured thereto a chuck 40, in which the shank of the drill steel is supported. The tappet 8 is guided within a bore in the chuck sleeve in the manner illustrated. It is accordingly evident that as the hammer piston reciprocates, the drill steel is 55 intermittently rotated.

The rotation release means, generally designated 1, is similar to that disclosed in a copending application to one John L. Reilly, Serial No. 56,166, filed Dec. 26, 1935, now matured into Patent No. 2,128,321, granted August 30, 1938, and comprises a floating ring 42 arranged in a recess 43 formed by cooperating annular grooves 60 formed in the rear faces of the ratchet ring and pawl carrier and surrounding the rearward portion of the latter, in the manner shown in Fig. 2. This floating ring 42 is not truly annular in the sense of having truly circular inner and outer 65 peripheries, but, as shown in Fig. 3, it possesses an outer peripheral surface coaxial with the rifle bar and pawl carrier axes, and it is adapted to be held against rotation at will by improved means to be later described. The inner wall of 70 the floating ring 42 is recessed at 44 to provide

portions which permit free engagement of the pawls 34 with the ratchet teeth 35 of the ratchet ring and portions 45 forming cam-like surfaces which, when engaged with the tips of the pawls, compress the latter into positions in which contact thereof with the ratchet teeth is precluded. The inner wall of the floating ring is formed with four identical recesses and cam-like surfaces terminating at the recesses, which permit movement of the pawls into engagement with the 10 teeth of the ratchet ring; but the cam-like surfaces in the ring are adapted to interrupt pawl contact with the ratchet teeth. Let it be assumed that the floating ring 42 is released for free rotation and it will turn with the pawl carrier, pawls and rifle bar; and the rifle bar and rifle nut and the associated ratchet and pawl mechanism will cause the hammer piston to rotate intermittently, and accordingly the hammer motor will operate in the conventional manner of rock drills of the automatic rotation, hammer type. This will be understood as soon as it is noted that the normal reaction of the tips of the pawls on the cam-like surfaces 45 of the floating ring is to maintain the ring in such 20 relative position to the pawl carrier as to permit maximum expansion of the pawls. For example, Fig. 3 shows the normal position relative to the pawl carrier of the ring 42 when such ring is free to turn. When, however, rotation of 30 the floating ring is precluded, the forward stroke of the hammer piston will cause the rifle bar to rotate, rotating therewith the pawl carrier, and the pawls will be depressed inwardly by their engagement with the cam-like surfaces of the 35 ring. When the return stroke of the hammer piston begins, the pawl carrier will begin to rotate freely instead of acting to hold the rifle bar stationary, for the tips of the pawls will be kept out of engagement with the ratchet teeth, and so 40 there will be nothing for them to react upon and compel rotation of the hammer piston. When it is desired to resume drill steel rotation, the floating ring 42 is released for free rotation with the pawl carrier, and the pawls will simply pick 45 up and carry the ring around with them as the rifle bar rotates. As soon as the ring is released, the pawls are permitted to move into engagement with the ratchet teeth. As this rotation release means is clearly described in the above 50 mentioned copending application, Serial No. 56,166, further illustration and description thereof are considered unnecessary.

Now referring to the improved fluid actuated control means for controlling rotation of the floating ring 42 of the rotation release means, it will be noted that arranged in a longitudinal bore 46 formed in the member 27, is a locking plunger 47 having an actuating piston 48. The bore 46 at the forward side of the piston 48 is vented to 60 atmosphere through a passage 49. The flow of actuating fluid to and from the bore 46 at the rear side of the actuating piston 48 is controlled by the throttle valve 19 of the hammer motor. The throttle valve 19, as shown in Fig. 2, has an axial bore 50 communicating with the chamber 20 in the throttle valve, and this bore 50 is connected by a radial passage 51 with a circumferentially extending groove 52 formed on the valve periphery. A passage 53 connects the valve 70 bore 17 with the bore 46 at the rear side of the piston 48, and the valve bore is vented to atmosphere through a vent port 54 connectible to the passage 53 by a circumferentially extending groove 55 formed on the valve periphery. When 75

the throttle valve 19 is in the position shown in Fig. 2, the bore 46 at the rear side of the piston 48 is vented to atmosphere through passage 53, groove 55 and vent port 54. When the throttle valve is rotated into the position shown in Fig. 5, the groove 52 is brought into communication with the passage 53; as a result pressure fluid may flow from the bore 50 in the throttle valve and through passage 51, groove 52 and passage 53 to the bore 46 at the rear side of the piston 48, the pressure fluid acting on the rear pressure area of the piston to force the locking plunger forwardly within its bore into locking engagement with the floating ring 42, thereby to hold the latter against rotation and to interrupt drill steel rotation, in the manner above described. When the supply of actuating fluid to the locking plunger piston is cut off, the passages in the throttle valve still permit the hammer motor to operate, so that steel rotation is interrupted while the hammer piston continues to actuate percussively the drill steel.

In the illustrative embodiment of the invention shown in Figs. 6 to 11, inclusive, the rotation release means is shown embodied in a hammer rock drill of the drifter type, and the hammer motor and piston structures are substantially similar to those described above, with the exception that in this instance the tappet for transmitting the hammer blows of the piston to the drill steel shank is omitted. The rotation release means, as in the embodiment of the invention above described, is identical to that disclosed in the copending application Serial No. 56,166 above referred to. Corresponding parts are designated by primed reference characters, in the similar structure. In this instance, however, the control of the locking plunger for the floating ring 42 is operable wholly independently of the throttle valve of the hammer motor. As shown most clearly in Fig. 9, arranged in a longitudinal bore 60 in a rear head block 61 is a rotary control valve 62 having an operating handle 63 conveniently located at the rear end of the hammer motor. In this instance, the handle 63 is located in adjacency to the control handle of the conventional throttle valve 64 of the drill hammer motor. Also arranged in the bore 60 is the actuating piston 65 for the locking plunger 66, the latter being guided within a bushing 67 arranged within the rear head. The rear head 61 is formed with a pressure fluid supply recess 68, to which pressure fluid may be supplied through a supply connection 69, and this recess 68 is connected to the bore 60 by a passage 70. Also communicating with the valve bore is a vent passage 71. The control valve is formed with a chamber 72 with which communicate ports 73 and 74 arranged at substantially right angles, and this chamber communicates directly with the bore 60 at the rear side of the piston 65 of the locking plunger. When the valve 62 is in the position shown in Fig. 8, the bore 60 at the rear side of piston 65 is vented to atmosphere through the chamber 72 in the valve and port 73 communicating with the vent passage 71. When the valve 62 is rotated in the position shown in Fig. 11, the valve chamber 72 is connected to the fluid supply recess 68 through the port 74 and passage 70, so that pressure fluid may flow from the supply recess through the passage 70 and port 74 to the valve chamber 72 and thence to the bore 60 at the rear side of the piston 65; the pressure fluid acting on the rear pressure area of the piston to move the locking plunger forwardly into locking engagement with the floating ring 42, to hold the latter against rotation, thereby to interrupt drill

steel rotation. The valve 62 may be held in either of its positions by a spring-pressed plunger 75 projecting within a circumferentially extending groove 76 on the valve periphery and adapted to project within certain of spaced notches 77, in the different valve positions. Otherwise, this embodiment of the invention is the same as that above described.

As a result of this invention, it will be noted that an improved rotation release means is provided for a hammer rock drill whereby drill steel rotation may be interrupted at will while the hammer piston of the hammer motor continues to operate. It will further be noted that by providing a fluid actuated locking means for the floating ring of the rotation release means, drill steel rotation may be quickly and easily interrupted at the will of the operator. Further, by the provision of the control for the fluid actuated locking plunger by the throttle valve of the drill, it is possible for the operator to control rotation release without removing his hand from the throttle valve handle. Other uses and advantages of the invention will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a rock drill, in combination, a pressure fluid actuated hammer motor for percussively actuating a drill steel, drill steel rotation mechanism for rotating the drill steel as the latter is percussively actuated including relatively rotatable ratchet and pawl carrier elements, one of which is stationary and the other of which is rotatable, means for interrupting drill steel rotation while percussive actuation of the drill steel continues including pawl trip means normally rotatable with said rotatable element and fluid actuated means for holding said trip means against rotation to effect release of the pawls of the pawl carrier element from the teeth of said ratchet element, and a throttle valve embodied in the drill for controlling the flow of actuating fluid to both said hammer motor and said fluid actuated means.

2. In a rock drill, in combination, a pressure fluid actuated hammer motor for percussively actuating a drill steel, drill steel rotation mechanism for rotating the drill steel as the latter is percussively actuated including relatively rotatable ratchet and pawl carrier elements, the pawls of the carrier element yieldingly engaging the teeth of the ratchet element and having means for yieldingly pressing them into engagement with the ratchet teeth, a throttle valve for controlling the supply of actuating fluid to said hammer motor, means for interrupting drill steel rotation while percussive actuation of the drill steel continues including pawl trip means normally freely rotatable while held against substantial bodily movement with respect to said ratchet and pawl carrier elements for effecting release of the pawls from the teeth of the ratchet element against the action of said yielding pawl pressing means, and fluid actuated means for holding said pawl trip means against rotation to effect pawl release, and a control valve embodied

in the drill and operable independently of said throttle valve for controlling the flow of actuating fluid to said fluid actuated means.

3. In a rock drill, the combination with drill steel rotation mechanism including relatively rotatable ratchet and pawl carrier elements, a rifle bar connected to the rotatable one of said elements, operative connections between said rifle bar and a drill steel to be rotated, and means for holding the other of said elements against rotation, of means for interrupting drill steel rotation comprising a normally rotatable member adapted to be held stationary for effecting release of the pawls from the teeth of said ratchet element, and fluid-actuated means for holding said pawl-release member stationary.

4. In a rock drill, the combination with drill steel rotation mechanism including relatively rotatable ratchet and pawl carrier elements, a rifle bar connected to the rotatable one of said elements, operative connections between said rifle bar and a drill steel to be rotated, and means for holding the other of said elements against rotation, of means for interrupting drill steel rotation comprising a normally rotatable member adapted to be held stationary for effecting release of the pawls from the teeth of said ratchet element, fluid-actuated means for holding said pawl-release member stationary, and a control valve embodied in the drill for controlling the supply of actuating fluid to said fluid-actuated means.

5. In a rock drill, the combination with drill steel rotation mechanism including relatively rotatable ratchet and pawl carrier elements, operative connections between one of said elements and a drill steel to be rotated and means for holding the other element against rotation, of means rotatable about the axis of rotation of said rotatable element for effecting interruption of drill steel rotation during drill operation and while the operative connections between said rotatable element and said drill steel are maintained, fluid-actuated means for controlling said rotation-interrupting means, and means embodied in the drill and operable at will for controlling the flow of actuating fluid to said fluid-actuated means.

6. In a rock drill, the combination with drill steel rotation mechanism including relatively rotatable ratchet and pawl carrier elements, operative connections between one of said elements and a drill steel to be rotated and means for holding the other element against rotation, of means including a rotation control element arranged for rotation relative to but normally floating with said rotatable element, and means for holding the same stationary during drill operation for interrupting drill steel rotation, a fluid-actuated piston for controlling said holding means and a valve member embodied in the drill for controlling the supply of actuating fluid to said piston.

7. In a rock drill, the combination with drill steel rotation mechanism including relatively rotatable ratchet and pawl carrier elements, operative connections between one of said elements and a drill steel to be rotated and means for holding the other element against rotation, of means including a rotation-control element normally floating with said rotatable element, and means for holding the same stationary during drill operation for interrupting drill steel rotation, a fluid-actuated piston for controlling said control element of said holding means and a valve embodied in the drill and arranged coaxially with

said piston for controlling the supply of actuating fluid to said piston.

8. In a rock drill, the combination with drill steel rotation mechanism including relatively rotatable ratchet and pawl carrier elements, means for holding one of said elements against rotation, a rifle bar connected to the rotatable one of said elements and operative connections between said rifle bar and a drill steel to be rotated, of means for interrupting drill steel rotation comprising a normally rotatable trip member adapted to be held stationary for effecting release of the pawls from the teeth of the ratchet element, a member movable into engagement with said trip member for holding the latter stationary, and remotely located control means operable at will for effecting actuation of said holding member.

9. In a rock drill, in combination, a pressure fluid actuated hammer motor for percussively actuating a drill steel, drill steel rotation mechanism for rotating the drill steel as the latter is percussively actuated including relatively rotatable ratchet and pawl carrier elements arranged in coaxial relation and continuously held against substantial relative axial displacement longitudinally of the motor, the pawls of the carrier element yieldingly engaging the teeth of the ratchet element and having means for yieldingly pressing them into engagement with the ratchet teeth, and means for interrupting drill steel rotation while percussive actuation of the drill steel continues including pawl trip means also continuously held against substantial axial displacement longitudinally of the motor and control means therefor for effecting release of and holding the pawls, against the action of said yielding pawl pressing means, out of engagement with the ratchet teeth, and a remotely located control means operable at will for controlling said trip means control means.

10. In a rock drill, in combination, a pressure fluid actuated hammer motor for percussively actuating a drill steel, drill steel rotation mechanism for rotating the drill steel as the latter is percussively actuated including relatively rotatable ratchet and pawl carrier elements arranged in coaxial relation and continuously held against substantial relative axial displacement longitudinally of the motor, the pawls of the carrier element yieldingly engaging the teeth of the ratchet element and having means for yieldingly pressing them into engagement with the ratchet teeth, and fluid actuated means operable at will for interrupting drill steel rotation while percussive actuation of the drill steel continues comprising means also continuously held against substantial relative axial displacement longitudinally of the motor for effecting release of and holding the pawls, against the action of said yielding pawl pressing means, out of engagement with the ratchet teeth, and a valve embodied in the drill for controlling the flow of actuating fluid to said pawl release effecting and holding means.

11. In a rock drill, in combination, a pressure fluid actuated hammer motor for percussively actuating a drill steel, drill steel rotation mechanism for rotating the drill steel as the latter is percussively actuated including a ratchet ring fixed and continuously held stationary as regards rotative and longitudinal movements relative to the hammer motor, said ratchet ring having internal ratchet teeth, a pawl carrier arranged within and rotatable relative to said ratchet ring and having pawls yieldingly engaging the ratchet

ring and means for yieldingly pressing the pawls into engagement with the ratchet teeth, and fluid actuated means operable at will for interrupting drill steel rotation while percussive actuation of the drill steel continues comprising means normally freely rotatable relative to said ratchet ring for effecting when held against rotation release of and holding the pawls, against the action of said yielding pawl pressing means, out of engagement with the ratchet teeth, and a valve embodied in the drill for controlling the flow of actuating fluid to said pawl release effecting and holding means.

12. In a rock drill, the combination with drill steel rotation mechanism including relatively ro-

tatable ratchet and pawl carrier elements, means for holding one of said elements against rotation, a rifle bar connected to the rotatable one of said elements and operative connections between said rifle bar and a drill steel to be rotated, of means for interrupting drill steel rotation comprising a normally rotatable trip member adapted to be held stationary for effecting release of the pawls from the teeth of the ratchet element, a fluid actuated member movable into engagement with said trip member for holding the latter stationary, and means operable at will for controlling the supply of actuating fluid to said holding member for effecting actuation of the latter.

FRANK E. SINCLAIR. 15
